UNITED STATES PATENT OFFICE.

JOHN ERLE DOUGLAS, OF BIRMINGHAM, ALABAMA, ASSIGNOR TO AMERICAN CASTING COMPANY, OF BIRMINGHAM, ALABAMA, A CORPORATION OF ALABAMA.

FUEL PUMP.

Application filed June 6, 1923. Serial No. 643,716.

To all whom it may concern:

Be it known that I, JOHN ERLE DOUGLAS, a citizen of the United States, residing at Birmingham, in the county of Jefferson and State of Alabama, have invented certain new and useful Improvements in Fuel Pumps; and I do hereby declare the following to be a full, clear, and exact description of the invention, such as will enable others skilled in the art to which it appertains to make and use the same.

The present invention relates to improvements in injection pumps for use particularly with Diesel or the like internal combustion crude oil engines, and the invention has for an object to secure the injection of the fuel at constant pressure irrespective of the load upon the motor and to better obtain a spraying of the fuel at the fuel nozzle at greatly increased pressure resulting in the more perfect atomization at all speeds.

Another object of the invention lies in providing an improved injection pump in which the moving parts will be lubricated by the fuel oil under pressure, the pump being so packed as to avoid the leakage of fuel even at high pressure.

A further object of the invention is to provide an improved injection pump actuated continuously during the running of the motor and operating to draw from the fuel tank and circulate the fuel at all times, there being an automatic control device associated with the pump and with the engine governor for determining the amount of fuel to be delivered to the nozzle in the cylinder head and bringing an equal amount of fuel from the fuel tank.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side view of a crude oil engine having the improved pump and associated parts constructed and operating according to the present invention.

Figure 2 is an enlarged longitudinal section taken through the pump.

Figure 3 is an enlarged fragmentary side view, with parts shown in section showing the pump and adjacent parts.

Figure 4 is a similar view taken from the opposite side of the pump.

Figure 5 is an end view of the pump and its allied mechanism, and

Figure 6 is a section taken on line 6—6 in Figure 2.

Referring more particularly to the drawings, 1 designates in general an internal combustion crude or heavy oil engine of the Diesel or other type in which 2 is the crank shaft and 3 the cylinder. The fuel tank is indicated by the line 4 and is in connection with a fuel outlet pipe 5 leading to the pump casing 6. From the pump casing the fuel previously lifted through the pipe 5 is forced into the delivery pipe 8 by which it is conveyed to the nozzle which sprays it into the combustion chamber in the head of the cylinder 3. The general operation of an engine of this character is well known and such engines are usually equipped with governors of the centrifugal type in which 10 designates the centrifugal balls carried by the outwardly movable arms 11 secured to the vertically movable ring 12 which is adapted to raise and lower the shaft 13 in accordance with the speed of the engine, the governor being driven from the crank shaft 2 for instance by a belt 14 or other associated mechanical transmission.

The improved pump is constructed more particularly as illustrated in Figure 2 in which the casing 6 is shown to contain two superimposed and longitudinally extending cylinders 15 and 16, the lower cylinder being preferably situated close to the base of the casing while the upper cylinder is situated approximately midway the height of the same or slightly above the center line. In the cylinders are plungers 17 and 18 cut away at their rear ends and provided with rack teeth 19 and 20 disposed mutually toward one another in order to be engaged alike by the teeth upon a vibrating pinion 20' carried upon a shaft 21 transversely journaled through the casing between the two cylinders 15 and 16. The rack teeth 19 and 20 are disposed substantially coincident with the axis of the plungers 17 and 18 in order to insure that the thrust developed by the movement of the pinion is transmitted centrally and equally to avoid jamming of the plungers in the cylinders or undue friction upon the walls thereof and as a consequence to minimize wear and facilitate

the free action of the pump. At one end of the block or casing 6 are plugs 22 and 23 screwed into the ends of the cylinders to enable access to be had thereto for the purpose of cleaning or removing the plungers.

5 The pipe 5 conveying oil from the oil tank 4 is connected to the pipe section 24 projecting from the lower forward portion of the pump casing 6, in which pipe section 10 is a seat for the downwardly seating check valve 25 having the perforated guard plate 26 thereabove communicating directly with the open end of the lower cylinder 15. A vertically disposed threaded opening 27 is 15 made in the pump casing or block 28 containing also a similarly downwardly seating check valve 29 communicating at its under side with the open end of the lower cylinder 15. This block communicates with 20 a transverse passage 31 leading to the open adjacent end of the upper pump cylinder 16 and to the pipe 8 which delivers the fuel to the nozzle, the pipe being provided with a screw threaded connection 32 by which 25 it is secured in fluid-tight fashion to the casing.

The valve 29 is carried by a stem 30 extending upwardly and guided at its upper end in a cap 33 threaded into the top of the 30 casing. The stem is provided with a shoulder or flange 34 against the upper edge of which a coil spring 35 engages in the act of forcing yieldably the valve 29 to its seat. A lifting arm 36 straddles a reduced part 35 of the valve stem 30 beneath the flange 34, said lifting arm being fast on a shaft 38 journaled transversely in the casing and projecting at one end, as seen in Figure 4, to receive an arm 39.

40 The arm 39 projects above the shaft 38 to which it is fixed and is pivotally coupled to a link 41 having at its free end, a yoke 42 occupied by a tapering or wedge shaped bar depending from the governor shaft 13 and pivoted thereto as indicated at 44 in 45 Figures 1 and 5 in order that the bar may swing in the same direction with the link 41 and in the direction of the slot in the yoke which also contains a finger 45 projecting upwardly from a rock shaft 46 extending transversely through the casing and having a continuous oscillating movement imparted by the moving parts of the engine. The finger 45 is so disposed that 50 it bears against one wedge-shaped side face of the bar, while the bar engages against the end of the yoke. An appropriate guide 55 may be provided for the yoke and link 41.

The bar carried by the governor may be 60 of the same shape as in my co-pending application filed April 18, 1923, Serial No. 633037 or it may be as shown herein where the bar is indicated at 43 having a lower cut-out portion slidably receiving a wedge 65 7 carried by an arm 37 pivoted to the bar

and held under the pressure of a spring 37 by which the wedge 7 is normally held down. A cord is attached to the arm 37 for drawing the wedge up.

One mechanism for securing the reciprocation of the pump plungers and also the oscillation of the rock shaft 46 is illustrated in Figures 1 and 3 in which an eccentric 50 upon the crank shaft 2 is utilized to move the eccentric strap 51 and also this 55 eccentric strap the arm 52 secured thereto and lying along one side of the pump casing 6. At its free end this arm 52 is slotted as indicated at 53 receiving therein a pin 54 which projects from an arm 55 upstanding from the pump shaft 21 upon which the pump pinion is mounted. Upon this same shaft 21 is an eccentric 55 having a strap secured to an arm 56 which is pivotally coupled as indicated at 57 to a depending arm 58 upon the rock shaft 46.

At 60 is shown a by-pass about the valve 29. At the base of the by-pass is a check valve 61 operating toward and from a seat 62 and urged to a closed position by a coil spring 63. The check valve may be a unit assembly inserted and removed through use of the plug 64.

In operation, as the engine shaft 2 rotates it will revolve the governor balls 10 and also reciprocate the rod 52 by which an oscillating movement is communicated through the arm 55 and shaft 21 to the pinion 20. Due to the gear connection between the pinion and the plungers 17 and 18, the latter will be reciprocated in the cylinders 15 and 16 but the plungers will move in constantly relatively reverse directions. When for instance the lower plunger 17 is moving to the right in Figure 2, the upper plunger 18 is moving to the left.

The plunger 17 draws oil from the fuel tank on its back stroke. When the plunger 17 goes forward the fuel in front of it is caused to open the check valve 29 against spring pressure and the fuel passes into the space in front of the receding plunger 18. When the top plunger is caused to displace the fuel in front of it the oil must go through the pipe 8 to the nozzle until 115 the check valve 29 is opened mechanically by the governor controlled mechanism. That is, the governor controls the mechanical opening of the valve 29 against pressure in the top cylinder. As soon as the 120 valve 29 is mechanically opened, the fuel in front of the plunger 18 is bypassed in front of the plunger 17. As soon as the valve 29 is opened mechanically, the valve 25 closes and no more fuel is drawn from 125 the tank. This causes the plunger 17 to draw only the amount of fuel from the tank that the plunger 18 is injecting into the engine through the nozzle.

The relief valve 61 is held closed by a 130

powerful spring. The relief valve 61 is only opened when an extreme predetermined pressure is built up in the upper cylinder. The pressure necessary to open relief valve 61 is much greater than that necessary to inject the oil through the nozzle and is only attained when some obstruction is formed in the nozzle. If we did not have the relief valve 61 and the nozzle passage was obstructed, something would have to break.

The form of governor wedge 7 shown is used where it is desirable to speed up the engine independent of governor control. The arm is attached to the governor stem in the usual manner. When it is desired to speed up the engine a cord or wire attached to the link 37 is pulled, causing the wedge 7 to be raised and allowing more fuel to go into the engine because of the relatively later mechanical opening of the valve 29. When the tension on the wire or cord is slackened the spring brings the link 37 and the wedge 7 back to their former position and puts the engine back under the control of the governor.

If the finger 45 was connected to the yoke 41, by means of a pin, the valve between the upper and lower cylinders would begin to open as soon as the upper piston started its power stroke. Naturally in this case no fuel would be injected through the nozzle. Now if this pin were a loose fit so that the action of lifting the valve lagged behind the action of the top piston, the oil displaced by the top piston during this time of lagging action would be forced through the nozzle and, as soon as the lost motion between pin and hole were taken up and valve opened, the balance of the oil displaced by the top plunger would travel around under the valve.

We are using a wedge instead of a pin. When the wedge is lowered to the point where it just fits the space between the finger 45 and the yoke 41, when the finger 45 is at its farthest back position, any movement of the finger 45 will lift the valve off its seat. This case is similar to that described if the finger and yoke were pinned together. Any lifting of the wedge will allow action of the yoke to lag behind the action of the finger and we have a condition similar to a pin in a loose hole, some oil will be forced through the nozzle.

We, therefore, see that the amount of oil injected per stroke of the pump is determined by the amount of lost motion or lag between the action of the finger and yoke. As the action of the finger is controlled by the rotation of the crank shaft, we can measure this lost motion or lag in degrees of rotation of the crank shaft.

When the engine speeds up, the governor lowers the wedge, the amount of lost motion between the finger and yoke is reduced,

there is less lag between the forward motion of the finger and the yoke, and a smaller amount of the oil in front of the plunger is forced through the nozzle because fuel is forced through the nozzle during a smaller degree of rotation of the crank shaft. In other words, the governor controls the amount of fuel supplied to the engine by reducing or increasing the angle of rotation of the engine during which injection takes place.

It is obvious that various changes and modifications may be made in the details of construction and design of the above specifically described embodiment of this invention without departing from the spirit thereof, such changes and modifications being restricted only by the scope of the following claims.

What is claimed is:

1. A fuel pump comprising an initial pump for drawing the fuel from a source of supply, a final pump for drawing the charge of fuel from the initial pump and supplying same to the motor, a check valve disposed between said pumps for preventing back flow, and means to positively open said check valve despite the pressure in the final pump.

2. An improved fuel pump comprising an initial pump for withdrawing a charge of fuel from a source of supply, a final pump for drawing said charge from the initial pump and for circulating the charge to the combustion chamber of the motor, a yieldably closed check valve disposed between said pumps and adapted to permit flow only from the initial toward the final pump, and means for positively opening said check valve proportionately to the speed of the engine.

3. An improved fuel pump comprising an initial pump, a final pump in communication therewith, a spring-pressed check valve disposed between said pumps, means for positively opening and holding open said check valve whereby to permit the final pump to return its charge to the initial pump for drawing in fresh charges, and governing means on the engine connected to said check valve opening means whereby to open the check valve proportionately to the speed of the engine.

4. In combination with an internal combustion engine, and a governor driven thereby, a pair of communicating pumps, one of said pumps being in communication with a source of fuel supply and the other pump being in communication with the combustion chamber of the engine, a check valve disposed between said pumps, means for positively opening said check valve, said means being coupled to the governor and actuated proportionately to the speed of the engine, and means associated with said valve opening means for varying the lifting of

- the valve independently of the action of the governor.
5. In combination with an internal combustion engine, and a governor therefor, a pair of communicating pumps, a check valve controlling the communication between said pumps, one of said pumps being in communication with a source of fuel supply and the other pump being in communication with the motor, means for independently and positively lifting said check valve from its seat, said means being driven from the engine, control means for said last named means coupled to said governor, and movable therewith on variations in speed of the engine, and a hand actuated device associated with said last named means for controlling the throw of the valve lifting means independently of the action of the governor.
10. A pump comprising initial and final chambers in communication respectively with a source of fuel supply and with an internal combustion engine, said chambers being in communication, alternately acting plungers in said chambers, a yieldably closed check valve controlling the communication between said chambers, a rock lifting arm for positively moving said check valve over its seat, a reciprocating yoke coupled to actuate said arm, an adjustable governor arm extending into said yoke, a shiftable wedge carried by said governor arm, and means for operating in said yoke and in conjunction with said arm and wedge to reciprocate the yoke variably dependent on the adjustment of said governor bar and the wedge.
15. A pump comprising a casing having adjoining and communicating chambers disposed in communication, alternately acting plungers in said chambers, a yieldably closed check valve between said chambers, means for positively lifting said check valve from its seat and a by-pass between said chambers.
20. A fuel pump comprising a casing having adjoining and communicating chambers, alternately acting plunger therein, a yieldably closed check valve controlling the communication between said chambers, a by-pass about said check valve, a relief valve in said by-pass and means for positively opening said check valve.
25. A fuel pump comprising in combination with an internal combustion engine, a pump casing having pump cylinders, plungers therein, a gear to operate the plungers, an arm connected to the gear, an eccentric turned by the engine, and an eccentric rod having a loose connection with said arm whereby the mid-stroke of the eccentric may impart a high rate of speed to the plungers.
30. A fuel pump comprising a casing having cylinders in connection with a fuel supply and with the combustion chamber, plungers in the cylinders, means to drive the plungers, a check valve between the cylinders, a governor driven by the engine, and means moved by the governor for opening the check valve whereby to control the interval of injection in inverse proportion to the speed of the engine.
35. A fuel pump comprising a casing in connection with a source of fuel supply and with the combustion chamber of a motor having a nozzle valve, pump plungers in the casing, a mechanically opened valve between the plungers adapted to permit an instantaneous drop of pressure in the fuel delivery nozzle whereby to effect an instantaneous and positive closing of the nozzle valve thereby eliminating the nozzle drip.
40. A fuel pump comprising a casing having adjoining and communicating chambers disposed in communication, alternately acting plungers in said chambers, a yieldably closed check valve between said chambers, a
